UNITED STATES PATENT OFFICE.

FRANK H. HARRIS, OF TOLEDO, OHIO.

VELOCIPEDÉ.

SPECIFICATION forming part of Letters Patent No. 396,083, dated January 15, 1889.

Application filed April 10, 1888. Serial No. 270,194. (No model.)

To all whom it may concern:

Be it known that I, FRANK H. HARRIS, a citizen of the United States, residing at Toledo, in the county of Lucas and State of Ohio, 5 have invented certain new and useful Improvements in Velocipedes, of which the following is a specification, reference being had therein to the accompanying drawings.

This invention relates to new and useful 10 improvements in velocipedes; and the invention relates more specifically to the improvement in the construction of the seat and elastic seat-support, and, further, in the improved means for connecting the backbone to the 15 forked standard of the front wheel, all as more fully hereinafter described.

In the drawings which accompany this specification, Figure 1 is a perspective view of the backbone and front standard of a velocipede 20 to which my improvements are applied. Fig. 2 is a vertical central longitudinal section of Fig. 1. Fig. 3 is a plan of the front end of the backbone, and Fig. 4 is a plan of the metallic seat-frame.

25 A represents the forked standard, which carries the front wheel of a three-wheel velocipede of usual construction. B is the steering-handle, secured to the upper end of this standard and preferably cast integral therewith. CC' are rearwardly-projecting brackets integrally formed with the forked standard. D is the backbone, supported upon the hind wheels and supports the rider upon the saddle F, and E is the head of the backbone, 30 which pivotally engages with the brackets C C', all the parts being constructed and arranged in the usual and known manner, except as more fully hereinafter described. The bracket C is provided with the upwardly-projecting pintle G, which forms a step upon which the lower end of the head E engages by means of the conical socket formed therein. The bracket C' is cylindrically apertured, and a pivot-pin, H, is removably secured therein by means of the set-screw I or otherwise, and engages with its lower end into a conical socket formed in the upper end of the head E of the backbone.

The backbone D is bifurcated its whole 45 length back of the head, gradually tapering from the head back toward its rear ends, where it is provided with suitable clamping-

boxes, K, for securing it to the hind axle, L. A suitable ornamental strengthening-web, M, may be placed between the bifurcations, as 55 in the usual manner.

a is a rearwardly-projecting lug or bracket cast integrally with the head and backbone, and to which the forward end of the saddle-frame is pivotally secured at b. The saddle-frame consists of the shank c, which at its forward end is provided with the ears d, by means of which it is pivotally secured to the bracket a, and of the skeleton seat-frame E, over which the leather or other suitable fabric is stretched 60 to form an easy and comfortable seat for the rider.

M' is the spring, formed of a single flat steel bar straight or curved, as fancy may dictate, and to the rear end of this spring the saddle-frame is suitably secured at f. The forward end of this spring is secured in position to support the weight of the rider by means of three cross-bars, g, h, and i, formed in the crotch of the backbone. The forward cross-bar, g, for the sake of additional strength, may be formed integrally with the bracket a, which to this end is provided with the rearward extension, j, and engages with such rearward extension between the bifurcations of 75 the shank of the saddle, whereby it arrests any lateral motion of the saddle-frame. The cross-bars h and i preferably form a loop upwardly inclined, whereby the cross-bar i bears upon the spring on top and the cross-bar h on 80 the bottom, while at the same time the lateral motion of the spring is counteracted by the sides of the loop. Thus by this manner of fastening the spring, the latter is supported against upward and downward displacement, 85 as well as against lateral displacement, and affords an easy and comfortable seat for the rider, which may be readily adjusted up or down by changing the curvature of the spring to suit different weight of riders, and which 90 is easily mounted and dismounted by the use of the single rivet or bolt.

95 By the means described for connecting the backbone to the standard all wear may be readily taken up, while in shipping the velocipede is easily put in a "knockdown" condition without having any loose small parts which are apt to become lost, the pivot H being simply held in its socket by the set-screw I.

What I claim as my invention is—

1. In a velocipede, in combination with the bifurcated backbone, a spring seat-support secured at one end to the seat-frame and slidingly engaging at the other end between cross-bars in the backbone, substantially as described.
2. The combination of the bifurcated backbone, the saddle-frame pivotally secured thereto at its forward end, and the spring seat-support held at its forward end between the cross-bars in the bifurcation of the backbone and secured at its rear end to the rear end of the saddle-frame, substantially as described.
3. In a velocipede, the combination of the saddle-frame provided with the shank *c*, bifurcated at its forward end and terminating in the ears *d*, the backbone provided with the bracket *a*, having the rearward extension *j*, engaging between the bifurcations of the saddle, and the seat-supporting spring *M'*, supporting the rear end of the seat, substantially as described.

4. The combination, with the bifurcated backbone *D*, of the saddle-frame provided with the shank *c*, bifurcated upon its forward end, the rearwardly-projecting arm *a* of the backbone, to which the forward end of said shank is pivotally secured, the rearward extension *j*, engaging between the bifurcations of the saddle-frame, the cross-bars *g*, *h*, and *i*, integrally formed with the backbone, and the seat-supporting spring *M'*, supported at its forward end between these cross-bars upon all sides and at its rear end to the saddle-frame, substantially as described.

In testimony whereof I affix my signature, in presence of two witnesses, this 13th day of March, 1888.

FRANK H. HARRIS.
